CLAIM

The ornamental design for a hexagonal trampoline frame with bracket, as shown and described.

DESCRIPTION

FIG. 1 is a view from above of a hexagonal trampoline frame with bracket of a first embodiment showing our new design; FIG. 2 is an enlarged broken away top view of a portion thereof taken from above the bracket; FIG. 3 is a perspective view of the portion shown in FIG. 2; FIG. 4 is a side elevational view of the portion shown in FIG. 2; FIG. 5 is a top perspective view thereof; FIG. 6 is a view from above of a hexagonal trampoline frame with bracket of a second embodiment showing our new design; FIG. 7 is an enlarged broken away top view of a portion thereof taken from above the bracket; FIG. 8 is a perspective view of the portion shown in FIG. 6; FIG. 9 is a side elevational view of the portion shown in FIG. 6; and, FIG. 10 is a top perspective view thereof. The broken lines in the figures are for the purpose of illustrating portions of the hexagonal trampoline frame with bracket which form no part of the claimed design.
